UNITED STATES PATENT OFFICE.

WILLIAM ROEBER, OF NEW YORK, N. Y.

DESIGN FOR AN INKSTAND.

SPECIFICATION forming part of Design No. 21,387, dated March 8, 1892.

Application filed February 1, 1892. Serial No. 419,994. Term of patent 7 years.

To all whom it may concern:

Be it known that I, WILLIAM ROEBER, of the city, county, and State of New York, have invented a new and original Design for Ink-stands, of which the following is a full, clear, and exact specification.

Reference is to be had to the accompanying drawings, forming a part of this specification, in which similar letters of reference indicate corresponding parts in both the figures.

Figure 1 is a perspective view of an inkstand embodying my new design, and Fig. 2 is a plan view thereof.

The design consists in the novel configuration and ornamentation shown.

The body A has a flat top, and the lines of said body at all sides depart in an outward and downward direction to the base, and the legs B are disposed at the four corners of said body. At the front a ledge C is projected from the body, and its flat upper face is relieved by a marginal upwardly-ranging flange c.

Said front also has produced thereon two rectangular figures D D', divided into panels d d'.

In the top surface of the body A circular openings a a appear, and in the rear of and between said openings appears a neck a', elliptical in plan view and tapering, which rises considerably above the top surface of the body. At the front the flat top surface is broken by a longitudinally-extending concave depression a². The continuity of the marginal flange c of the ledge C is broken by recesses c' c', the same appearing near the ends of said ledge and in alignment with each other.

I claim—

The design for an inkstand, herein shown and described.

WILLIAM ROEBER.
